Fig. 1.

UNITED STATES PATENT OFFICE.

HENRY GUY CARLETON, OF NEW YORK, N. Y., ASSIGNOR TO THE CARLETON ELECTRIC COMPANY, OF SAME PLACE.

FASTENING DEVICE.

SPECIFICATION forming part of Letters Patent No. 654,383, dated July 24, 1900.

Application filed February 3, 1900. Serial No. 3,793. (No model.)

To all whom it may concern:

Be it known that I, HENRY GUY CARLETON, a citizen of the United States, and a resident of New York, county of New York, and State 5 of New York, have invented certain new and useful Improvements in Fastening Devices, fully described in the following specification and the accompanying drawings, forming a part of the same.

10 This invention relates to certain improvements in locking devices, and is more particularly intended for use as a window-sash fastener. The invention is, however, applicable to other uses and may be used in any place 15 where it is desired to lock a slide or other similar device which moves in ways.

One of the objects of the invention is to produce an improved locking device for use with window-sashes or other slides moving 20 in ways in which the movable locking member will be electrically controlled.

A further object of the invention is to produce a locking device for use with window-sashes or other slides moving in ways in 25 which the locking member is normally out of action and in which a magnet is used to hold the device out of action, the device being thrown into operation in case a movement of the slide is attempted while the magnet 30 net is inoperative.

A further object of the invention is to produce an improved locking device for window-sashes and other slides which will embody an alarm mechanism, so that if any attempt is 35 made to tamper with the sash or slide a notification thereof will be given.

With these and other objects in view the invention consists in certain constructions and in certain parts, improvements, and combinations, as will be hereinafter fully described and then more specifically pointed out in the claims hereunto appended.

In the accompanying drawings, which form a part of this specification, and in which like 45 characters of reference indicate the same parts, Figure 1 indicates a side elevation partly in section, of a portion of a window frame and sash provided with the improved locking device. Fig. 2 is a side elevation 50 showing the parts in a different position, with the circuit closed through the alarm

mechanism. Fig. 3 is a section on the line 33 of Fig. 1.

Referring to the drawings, which illustrate a concrete embodiment of the invention as 55 applied to a sash-fastener, 1 indicates a sash-frame, and 2 indicates the window-frame in which the sash moves, the said frame being provided with ways 3, which serve to guide the sash, as is usual.

While the locking device might be located outside the window-frame and at any suitable point along the movement of the sash, the window-frame 2 is preferably provided with a recess 4, in which the movable locking member and its operating parts are contained. The recess 4 is closed by a plate 5, secured to the frame in any suitable manner, said plate being provided with a slot 6. The movable locking member may be variously 60 constructed. In the form shown it consists of a hook 7, provided with an elongated slot 8, through which passes a pivot 9. The movable locking member is therefore capable of a rocking movement about its pivot and a 65 sliding movement with respect thereto. The locking member 7 is normally held in such a position that the pivot 9 is at the top of the slot by means of a spring 10, which is connected to the pivot and to a point 11 on the 70 member.

Any suitable means may be provided with which the locking member co-operates. Preferably, however, and as in the construction shown, the sash carries a ratchet 12, which 85 is provided with a plurality of teeth for a purpose to be hereinafter mentioned. The sash also preferably carries means for normally holding the hook in an inoperative position. While this means may be variously 90 constructed, it preferably consists of a cam-surface 13, which in the construction shown is formed in one piece with the ratchet 12.

As has been indicated, the locking member or hook 7 is normally held in inoperative position. It may be thrown into engagement with the locking device on the sash in any suitable manner. In the construction shown a bearing-spring 14 is provided, said bearing-spring being secured to a bracket 15. This 95 bracket may be, as shown, formed of insulating material, or in case it is formed of metal

the spring 14 will be insulated therefrom by a washer. Any suitable means may be provided for holding the locking member or hook in inoperative position. Preferably, however, this will be effected by means of a magnet 18, the armature 19 of which is carried by the locking member 7, although the said member might itself form the armature for the magnet if desired. The magnet is preferably so located that its pole-piece will be close to its armature when the movable hook 7 is thrown into inoperative position by the cam-surface 13. By so arranging the magnet with relation to its armature only a small magnet and little battery power is necessary to operate the locking member, since the magnet does not actually withdraw the locking member, but only holds it in inoperative position, the member being lifted into the field of the magnet by the cam-surface 13.

An alarm mechanism, which may consist of the usual electric bell 20, is provided, and the alarm mechanism is preferably so arranged that the circuit thereof will be controlled by the locking member.

Any suitable circuit or circuits may be employed for the devices thus far described. In the construction shown the battery is indicated at 21, said battery being connected by a wire 22 with any suitable circuit-closing device—such, for instance, as a push-button 23. From the push-button 23 a wire 24 leads to the coils of the magnet, and the circuit then runs by the metallic portions of the lock to a binding-stud 25, mounted on the movable member 7. From the binding-stud 25 a wire 26 leads to the battery.

The alarm-circuit shown is formed by a branch wire 27, which leads from the wire 22 to the bell. From the bell a wire 28 leads to a spring-contact 29, which is carried on the bracket 15 before described. This spring-contact 29 is normally out of contact with the stud 25, but lies in the path of said stud, so that the circuit will be closed when the locking member is given the sliding movement on its pivot before described.

The operation of the construction is as follows: The normal condition of the parts is shown in Fig. 1. If it be desired to open the window, the push-button 23 is depressed, closing the circuit through the magnet by the wires 22 24, the lock-casing, and the wire 26. As has been before indicated, the movable locking-hook 7 is held in the field of the magnet by means of the cam-surface 13. When the circuit is closed, as before described, the magnet attracts its armature 19 and the locking member is held in inoperative position, so that the sash is free to move and carry the ratchet 12 by the point of the hook. If, however, an attempt be made to move the sash when the magnet is deenergized, the parts will be thrown into the position indicated in Fig. 2. In this position it will be seen that a slight upward movement of the sash will cause the hook to ride off the cam-surface 13

and to engage the upper tooth of the ratchet 12. A farther movement of the sash causes the movable member to slide upward on its pivot and brings the stud 25 against the spring-contact 29. This closes the circuit, the current going from the battery by the wires 22 27 through the bell, by the wire 28 to the contact 29, and from the binding-stud 25 by the wire 26 back to the battery 21. The alarm is thus sounded and continues to sound until the sash is restored to its original position and the hook drawn back by the spring 10, so that the stud 25 is moved away from the contact 29.

By providing the ratchet with a number of teeth, as shown, it will be seen that the sash may be locked in any desired position. In the construction shown the ratchet is provided with three teeth; but this number may be increased, if desired. If, for instance, it be desired to lock the sash in a position in which the window is partly open, the circuit is closed and the sash raised until the hook is opposite one of the teeth of the ratchet—say, for instance, the third tooth. The circuit is now broken and the spring 14 throws the locking-hook inward, so that it overlaps the ratchet-tooth. Inasmuch as the hook was out of engagement with the sash when the same was raised, it was given no sliding movement on its pivot. It consequently remains in the position shown with relation to its pivot, (indicated in Fig. 1,) though in its inward position and engaging the ratchet. Any attempt, however, to raise the sash any farther without closing the circuit at the circuit-closer will result in giving the hook a sliding movement on its pivot and closing the circuit.

While the invention is shown as embodied in a sash-fastener, it is to be understood that it has a much wider application. It might, for instance, be used to lock vertically-sliding elevator-doors, the sliding covers of desks, and, in fact, to lock any slide which has a movement in ways. It is to be understood, furthermore, that the specific construction by which the invention is carried into effect may be considerably varied. The invention is not, therefore, to be limited to the specific details of construction which have been hereinabove described.

What is claimed is—

1. The combination with a slide, of ways in which it moves, a locking device located in the path of movement of the slide, and electrical means by which the action of the locking device is controlled, substantially as described.

2. The combination with a slide, of ways in which it moves, a locking device located along the path of movement of the slide, a magnet for controlling the action of the locking device, an alarm mechanism, and means whereby an attempt to move the slide when the locking device is in operative position will cause the alarm to sound, substantially as described.

3. The combination with a slide, of ways in which it moves, a movable locking member located along the path of movement of the slide, a magnet for controlling the operation of said locking member, a suitable circuit for the magnet, an alarm mechanism, a suitable circuit therefor, and means whereby a movement of the slide when the locking member is in operative position closes the circuit of the alarm mechanism, substantially as described.

4. The combination with a slide, of ways in which it moves, a movable locking member located along the path of movement of the slide, and a magnet for controlling the movement of the member, substantially as described.

5. The combination with a slide, of ways in which it moves, a normally-inoperative locking member located along the path of movement of the slide, means whereby a movement of the slide causes the locking member to be thrown into operative position, and a magnet for holding the locking member out of operative position, substantially as described.

6. The combination with a slide, of ways in which it moves, a normally-inoperative pivoted locking member located along the path of movement of the slide, means whereby a movement of the slide causes the locking member to be thrown into operative position, and a magnet for holding the locking member out of operative position, substantially as described.

7. The combination with a slide, of ways in which it moves, a normally-inoperative locking member located along the path of movement of the slide, a magnet for holding the locking member in inoperative position, an alarm mechanism, a suitable circuit therefor, and means controlled by the locking member for closing the circuit, substantially as described.

8. The combination with a slide, of ways in which it moves, a pivoted locking member located along the path of movement of the slide, said member having a sliding movement with respect to its pivot, means for controlling the pivotal movement of the locking member, an alarm mechanism, a circuit therefor, and means whereby the sliding movement of the locking member closes the circuit, substantially as described.

9. The combination with a slide, of ways in which it moves, a pivoted locking member located along the path of movement of the slide, said member having a sliding movement with respect to its pivot, a magnet for controlling the pivotal movement of the locking member, an alarm mechanism, a circuit therefor, and means whereby the sliding movement of the locking member closes the circuit, substantially as described.

10. The combination with a slide, of ways in which it moves, a normally-inoperative pivoted locking member located along the path

of movement of the slide, said member having a sliding movement with respect to its pivot, a magnet for controlling the pivotal movement of the locking member, an alarm mechanism, a circuit therefor, and means whereby the sliding movement of the locking member closes the circuit, substantially as described.

75

11. The combination with a slide, of ways in which it moves, a pivoted locking-hook located in one of the ways, means on the slide with which the hook engages, and a magnet for controlling the operation of the hook, substantially as described.

80

12. The combination with a slide, of ways in which it moves, a pivoted locking-hook located in one of the ways, means on the slide with which the hook engages, means also on the slide for normally holding the hook in such position that it does not engage the locking means, and a magnet for retaining the hook in its inoperative position, substantially as described.

85

13. The combination with a slide, of ways in which it moves, a pivoted locking-hook located along the path of movement of the slide, said hook being arranged to have a sliding movement on its pivot, coöperating means on the slide with which the hook engages and by which the hook is given its sliding movement when the slide is moved, means for normally holding the hook out of engagement with the coöperating means, a magnet for holding the hook in its inoperative position, an alarm mechanism, a suitable circuit therefor, and means whereby the sliding movement of the hook closes the said circuit, substantially as described.

90

14. The combination with a slide, of ways in which it moves, a pivoted locking-hook located along the path of movement of the slide, a ratchet with which the hook may engage when the slide is moved, a cam-surface operating to turn the hook on its pivot into inoperative position, and a magnet for retaining the hook in inoperative position, substantially as described.

105

15. The combination with a slide, of ways in which it moves, a locking member, coöperating locking means on the slide with which the locking member may engage at a plurality of points, means for controlling the operation of the locking member, an alarm mechanism, a suitable circuit therefor, and means whereby a movement of the slide after the locking member is in engagement with the coöperating locking means at any point will cause the circuit to be closed through the alarm mechanism, substantially as described.

115

16. The combination with a slide, of ways in which it moves, a locking member, coöperating locking means on the slide with which the locking member may engage at a plurality of points, a magnet for controlling the operation of the locking member, an alarm mechanism, a suitable circuit therefor, and means controlled by the locking member whereby a

120

125

130

movement of the slide after the locking member is in engagement with the coöperating locking means at any point will cause the circuit to be closed through the alarm mechanism, substantially as described.

17. The combination with a slide, of ways in which it moves, a slotted locking member, a pivot for the member passing through the slot, a ratchet on the slide provided with a plurality of teeth, any one of which may be engaged by the locking member, a magnet for controlling the pivotal movement of the member, an alarm mechanism, and a suitable circuit therefor, one of the contacts of the circuit being carried by the locking member, whereby a movement of the slide after the locking member is engaged with the ratchet at any point will cause the circuit to be closed through the alarm mechanism, substantially as described.

18. The combination with a window-sash, of a ratchet carried thereby, ways in which

the sash moves, one of said ways having a recess therein, a pivoted locking-hook disposed in the recess, said hook having a sliding movement on its pivot, means on the sash for holding the hook out of engagement with the ratchet, a magnet for holding the hook in its inoperative position, an alarm mechanism, a circuit therefor, a contact on the hook with which said circuit is connected, a second contact against which the first contact strikes when the hook is moved by the ratchet, a spring for returning the hook, substantially as described.

In testimony whereof I have hereunto set my hand in the presence of two subscribing witnesses.

HENRY GUY CARLETON.
